UNITED STATES PATENT OFFICE.

CONYERS BUTTON, OF PHILADELPHIA, PENNSYLVANIA.

DESIGN FOR STOCKING FABRIC.

Specification forming part of Design No. **6,669**, dated May 27, 1873; application filed May 13, 1873.

To all whom it may concern:

Be it known that I, CONYERS BUTTON, of Philadelphia, Pennsylvania, have invented a Design for Stocking Fabric, of which the following is a specification:

My design is fully represented by the figure in the accompanying drawing, and consists of stripes A and B, alternated upon a plain ground a.

Each stripe A has at its opposite edges narrow ribs b, within which, and at either side of a center composed of three ribs, c, d, and e, are wider ribs or bars f f. The stripes B are composed of a series of narrow parallel bars, stripes, or ribs, arranged in the manner too clearly shown in the drawing to need description.

The continuity of the stripes may be broken at intervals, if desired, by dropping stitches, so as to produce the appearance of ribs h crossing the stripes at right angles; but this is immaterial, and forms no part of my design.

Irrespective of the colors employed, I claim—

The design for a stocking fabric, substantially as described, and as represented in and by the accompanying drawing.

In testimony whereof I have signed my name to this specification, in the presence of two subscribing witnesses.

CONYERS BUTTON.

Witnesses:

W.M. A. STEEL,
L. BOSWELL.
